UNITED STATES PATENT OFFICE.

IRVING JAYNE, OF EDWALL, WASHINGTON.

INTERNAL-COMBUSTION ENGINE.

1,318,684.

Specification of Letters Patent. Patented Aug. 19, 1919.

Application filed November 24, 1917. Serial No. 203,839.

To all whom it may concern:

Be it known that I, IRVING JAYNE, a citizen of the United States, residing at Edwall, in the county of Lincoln and State of Washington, have invented certain new and useful Improvements in Internal-Combustion Engines, of which the following is a specification.

This invention relates to an improved internal combustion engine and has as its primary object to provide a construction wherein in the engine will be fired at opposite sides of the piston and will thus be double acting to consequently develop a correspondingly increased power with but slight increase in constructional cost and weight.

The invention has as a further object to provide an engine of the type above set forth wherein the use of a piston rod and packing gland therefor will be eliminated and wherein in the connecting rods for the pistons will be attached to opposite sides thereof so that the stationary abutment for the piston may be employed as a mounting for the intake and exhaust valves for the firing chamber of the engine at the inner side of the piston as well as to receive the intake and exhaust pipes leading from the said chamber.

The invention has as a further object to provide a construction wherein by mounting the connecting rods at opposite sides of the piston, the several cranks of the crank shaft of an engine having more than one cylinder will be disposed adjacent each other to consequently distribute the weight of the pistons to the crank shaft accordingly and wherein a bearing will be provided beneath each piston to consequently reduce vibration to a minimum and provide a smooth running high speed engine.

And the invention has as a still further object to provide a construction wherein the stationary abutment for the piston will be water cooled and connected with the water jacket of the working cylinder of the engine so that water introduced into the said jacket will circulate through the said jacket.

Other and incidental objects will appear as the description proceeds. In the drawings wherein I have illustrated the preferred embodiment of the invention and wherein similar reference characters designate corresponding parts throughout the several views:

Figure 1 is a sectional view of my im-

proved engine showing the piston at the top of its stroke,

Fig. 2 is a similar view taken on the line 2—2 of Fig. 1 and looking in the direction 60 of the arrows, this view particularly illustrating the mounting of the intake and exhaust valves for the firing chamber at the inner side of the piston,

Fig. 3 is a view similar to Fig. 1 and 65 showing the piston at the bottom of its stroke,

Fig. 4 is a transverse sectional view taken on the line 4—4 of Fig. 1 and particularly showing the intake and exhaust valves for 70 the firing chamber at the outer side of the piston.

Fig. 5 is a transverse sectional view taken on the line 5—5 of Fig. 1 and showing the trunnions carried by the piston to receive 75 the connecting rods from the crank shaft, and

Fig. 6 is a fragmentary sectional view showing the manner in which the working cylinder of the engine is formed with slots 80 to receive the trunnions of the piston.

In carrying out the invention, my improved engine is formed with a crank case 10 upon which is mounted a working cylinder 11, the casting of which is formed, at 85 its lower extremity, with the upper section 12 of the crank case. The crank case is, as particularly shown in Figs. 1, 3 and 5 of the drawings, off set upon one side thereof as shown at 13. Journalled through the crank 90 case at the junction of the sections thereof, is a crank shaft 14 having suitable cranks 15. Rising from the bottom of the crank case is a bearing 16 which receives and supports the crank shaft between the said 95 cranks and extending upwardly from this bearing is a post 17 arranged axially of the working cylinder 11 and carrying at its upper end a hollow stationary abutment 18 disposed concentrically within the lower extremity of the said cylinder. Preferably the bearing 16, post 17 and abutment 18 form an integral structure. Snugly surrounding the abutment 18 and mounted to reciprocate within the working cylinder 11 105 is a hollow piston 19 formed upon opposite sides thereof, at its lower extremity, with lateral trunnions 20. These trunnions are received through vertical slots 21 formed in opposite sides of the cylinder 11 and at their 110 inner extremities are formed with squared bosses 22 to ride within the said slots for

guiding the piston in its vertical movement and holding the said piston against rotation. As particularly shown in Fig. 6 of the drawings, the trunnions 20 are carried by suitable ears or extensions 23 extending downwardly from the lower edge of the piston at opposite sides thereof and, as also best shown in this figure, the cylinder 11 is formed with similar extensions 24 at the slots 21 for receiving the trunnions 20 when the piston is shifted downwardly to the limit of its stroke. Journaled upon the trunnions 20 are connecting rods 25 which are secured to the cranks 15 of the crank shaft. These rods are, as particularly shown in Fig. 5, received within suitable off set housings or channels 26 upon opposite sides of the cylinder 11 and operatively connect the piston with the crank shaft for driving the said shaft.

In connection with the arrangement of the connecting rods 25, it is desired to direct attention at this point to the fact that in thus mounting the said rods at opposite sides of the piston, the stationary abutment is, as shall presently appear, left intact to receive the intake and exhaust valves for the firing chamber at the inner side of the piston as well as the intake and exhaust pipes for the said chamber while the use of a piston rod and packing gland therefor is eliminated. Furthermore, it will be noted that in thus mounting the connecting rods, the cranks of the crank shaft, in any instance where the engine was formed with more than one cylinder, would be disposed relatively close together and the several connecting rods from the pistons of the engine cylinders would accordingly also be spaced relatively close together at their points of connection with the crank shaft. The weight of the pistons would, therefore, be centralized upon the crank shaft at spaced points longitudinally thereof and at each of such points one of the bearings 16 provided would be disposed for rigidly supporting the crank shaft at the said points respectively. Vibration incident to the reciprocation of the engine pistons would consequently be materially reduced and the engine thus adapted for high speed work.

Surrounding the working cylinder 11 is a water jacket 27 and leading from the lower extremity of this jacket, at one side thereof, is a pipe 28 which is carried into the crank case 10 preferably at the junction of the sections thereof, as shown in Fig. 1, and is thence directed upwardly into the fixed abutment 18 to terminate adjacent the upper end of said abutment. Leading from the bottom of the abutment is a pipe 29 which is carried through the crank case 10 at the sides thereof opposite the pipe 28 and, as in the instance of this pipe, the pipe 29 is also preferably fitted through the crank case at the joint between the sections thereof. Communicating with the water jacket 27 at the upper end of the working cylinder is a pipe 30' which provides a discharge pipe from the said jacket. Thus it will be seen that water supplied through the pipe 29 into the abutment will circulate through the said abutment and thence through the pipe 28 into the jacket 27, from whence the water will be discharged out through the pipe 30'. The working cylinder 11 will consequently be effectually cooled as will also the stationary abutment, and in this connection it will be observed that since the inner end of the pipe 28 is carried to a point adjacent the upper end of the said abutment, air cannot trap within the abutment to prevent the said abutment from becoming completely filled with water.

As will now be seen, a firing chamber 30 is provided at the outer side of the piston while a similar firing chamber 31 is provided at the inner side of the said piston. The working cylinder is, at its upper extremity, formed with overhanging valve chambers above the off-set 13 of the crank case and mounted within the said valve chambers are intake and exhaust valves 32 and 33 normally closing the intake and exhaust ports for the firing chamber 30. Communicating with the said valve chambers respectively are intake and exhaust pipes 34 and 35. As will now be best observed upon reference to Figs. 1 and 3 of the drawings, the rods of the valves 32 and 33 are elongated to extend through the off-set 13 of the crank case and, at their lower extremities, are arranged to coöperate with a cam shaft 36 upon which are arranged suitable cams for opening the said valves. Communicating with the firing chamber 30, at its upper end, is a suitable spark plug 37.

Entering through the crank case 10 at the joint between the sections thereof and arranged upon opposite sides of the pipe 29 are intake and exhaust pipes 38 and 39 respectively, for the firing chamber 31. The pipes 38 and 39 extend within the crank case beneath the stationary abutment 18 and are thence, as particularly shown in Fig. 2 of the drawings, directed upwardly through the said abutment at opposite sides of the post 17. At its upper end, the abutment is formed with intake and exhaust ports communicating with the said pipes and opening into the firing chamber 31, and normally closing the ports are intake and exhaust valves 40 and 41 respectively adapted to seat in the upper end wall of the said abutment. The valves 40 and 41 are arranged axially of the upwardly directed terminals of the pipes 38 and 39 and the rods of the said valves are extended downwardly within the said pipe terminals and freely project through the walls of the pipes at the

angles therein. Swingly mounted upon one side wall of the crank case opposite the lower ends of the rods of the valves 40 and 41 are bell crank levers 42 and 43 respectively. The uppermost arms of these levers project horizontally within the crank case and are pivotally connected to the lower ends of the said valve rods while the other arms of the said levers extend downwardly within the crank case adjacent the inner side of the cam shaft 36. Connected to the horizontal arms of the levers and suitably engaged with the post 17, are springs 44 acting upon the said levers to normally close the valves 40 and 41. For opening the said valves, the cam shaft 36 is formed with suitable cams which are arranged to coöperate with the vertical arms of the levers confronting the said shaft. Thus, it will be seen that the cam shaft 36 will not only control the valves 40 and 41 but will also control the valves 32 and 33.

Formed through the upper extremity of the piston 19 at one side thereof is a firing port 45 for the firing chamber 31 and surrounding the piston at each side of the said port are piston rings 46 so that a charge within the chamber 31 cannot escape into the chamber 30. The stationary abutment 18 is, at its upper extremity, also equipped with a plurality of similar piston rings 47. Fitted through the wall of the working cylinder 11 upon one side thereof and at a point substantially midway of the end of the said cylinder is a suitable spark plug 48 and, as will be observed upon reference to Fig. 3 of the drawings, the port 45 of the piston is arranged to move into register with this plug when the piston is shifted downwardly to the limit of its stroke.

In operation, it is intended that a charge will be fired within the chamber 30 upon every other down-stroke of the piston while a charge will be fired within the chamber 31 upon every other up-stroke of the piston. Assuming the piston to be at the top of its stroke, as shown in Fig. 1, a charge is fired within the chamber 30 when the piston will be driven downwardly to rotate the crank shaft. At the same time, the proper cam upon the shaft 36 will swing the bell crank lever 43, as shown in Fig. 2, for immediately opening the exhaust valve 41 of the chamber 31. As the piston moves downwardly, this chamber will be cleaned through the exhaust pipe 39. Upon the upward movement of the piston, the proper cam upon the shaft 36 will swing the bell crank lever 42, when the intake valve 40 to the chamber 31 will be immediately opened. Thus, as the piston moves upwardly, a charge of fuel mixture will be drawn into this chamber through the pipe 38. At the same time, the proper cam upon the shaft 36 will be shifted to engage the rod of the exhaust

valve 33 of the chamber 30 and open the said exhaust valve so that when the piston is thus shifted upwardly, the chamber 30 will be cleaned through the exhaust pipe 35. When the piston then again moves downwardly, both of the valves 40 and 41 will be closed so that the charge within the chamber 31 will be compressed. At the same time, the proper cam upon the shaft 36 will open the intake valve 32 of the chamber 30 so that a charge of fuel mixture will be drawn into the said chamber through the pipe 34. Downward movement of the piston to the limit of its stroke will then bring the port 45 of the piston into register with the spark plug 48 so that the compressed charge within the chamber 31 will be fired to drive the piston upwardly. Coincident with the upward movement of the piston, the intake valve 32 would be closed and the charge drawn into the chamber 30 would be compressed therein by the piston. Consequently, when the piston again started downwardly, such compressed charge in the chamber 30 would be fired and the proper cam upon the shaft 36 would swing the bell crank lever 43, for opening the exhaust valve 41 of the chamber 31 so that this chamber would be cleaned by the piston. Thus, it will be seen that my improved engine will be double acting in its operation to consequently develop a corresponding increase in power. At the same time, this result is attained with but slight increase in the weight of the engine, as compared with an engine of the single acting type. Furthermore, it will be noted that my improved engine is characterized by structural simplicity so that but slight increase, as compared with an engine of the single acting type, will be involved in the cost of construction.

Having thus described the invention, what is claimed as new is:

1. In engine construction, a working cylinder, a hollow stationary abutment therein, a piston mounted to slide over the abutment within the said cylinder, firing chambers at opposite sides of said piston, intake and exhaust ports for one of said chambers, means for opening and closing said ports, intake and exhaust ports for the other of said chambers opening through the abutment, intake and exhaust pipes leading through the abutment and communicating with said last mentioned ports, means carried by the abutment for opening and closing the said last mentioned ports, and means for supplying a cooling fluid within the abutment around said pipes to contact therewith.

2. In engine construction, a crank case, a crank shaft journaled therethrough, a bearing rising from the crank case and supporting the said shaft, a working cylinder carried by the crank case, a post rising from

the said bearing, a stationary abutment supported by the said post within the working cylinder, a piston mounted to slide over the said abutment within the said cylinder and 5 connected with the crank shaft, firing chambers at opposite sides of said piston and provided with intake and exhaust ports, and means for opening and closing said ports.

3. In engine construction, a working 10 cylinder, a hollow stationary abutment therein, a piston mounted to slide over the abutment within said cylinder, firing chambers at opposite sides of the piston, intake and exhaust ports for one of said chambers,

means for opening and closing said ports, 15 intake and exhaust ports for the other of said chambers opening through the abutment, intake and exhaust pipes extending through the abutment and communicating with said last mentioned ports, means carried by the abutment for opening and closing said last mentioned ports and extending within said pipes, and means for introducing a cooling fluid into the interior proper of the abutment to contact with said 20 25 pipes.

In testimony whereof I affix my signature.

IRVING JAYNE. [L.S.]
